HANDLE OR THE LIKE

Robert Kenneth Unter, Roscoe, Ill., assignor to National Lock Co., Rockford, Ill., a corporation of Delaware

Filed May 10, 1961, Ser. No. 65,102

Term of patent 14 years

(Cl. D10—8)

FIG. 1 is a front elevational view of a handle or the like embodying my new design;

FIG. 2 is a side elevational view thereof;

FIG. 3 is a rear elevational view thereof;

FIG. 4 is an end elevational view thereof; and

FIG. 5 is a cross sectional view on the line 5—5 of FIG. 1.

The longitudinal groove member on the face of the handle is shaded to show contrast.

I claim:

The ornamental design for a handle or the like, substantially as shown and described.
